FUEL ENGINE

Cabell Carrington, South Pasadena, Calif., as
signor to Ellen P. Carrington, Pasadena, Calif.

Application February 2, 1931, Serial No. 512,859

2 Claims. (Cl. 123—33)

My invention relates to improvements in fuel injector valves in which the liquid fuel is forced under very high pressure into and through a cylinder containing air at a high pressure and temperature and thence through a conical nozzle in the form of a finely divided mist into the combustion chamber of the engine. My improvement is for use in connection with internal combustion engines using a fuel such as gasoline or a heavier liquid oil; and the objects of my improvement are, first, to provide a positive means of introducing a liquid fuel directly into an engine cylinder, the engine cylinder containing pure air under a pressure and at a temperature less than that required to produce spontaneous combustion; second, to eliminate in engines employing a compression pressure and temperature less than that required to produce spontaneous combustion the necessity for vaporizing a liquid fuel and introducing it through a carburation system in conjunction with the air supply before compression; third, to eliminate in engines using direct liquid fuel injection the necessity for a compression pressure and temperature in the engine cylinder sufficient to cause spontaneous combustion of the fuel; and, fourth, to provide a fuel injector valve capable of receiving from a source outside of the engine cylinder high pressure air from which none of the heat of compression has been removed.

I attain these objects by the mechanism illustrated in the accompanying drawings, in which—

Figure 1 is a vertical section of the entire mechanism; Fig. 2, a horizontal section of the mechanism along the line 2—2, Fig. 1.

Similar numerals refer to similar parts throughout the several views.

The cylindrical chamber 1 leads through the conical nozzle 2 directly into the engine cylinder 3. The needle or piston valve 4 is slidably mounted in the cylindrical mixing chamber 1 so that when it is depressed to its lowest position it seats on the walls of the conical nozzle 2 and closes the opening into the engine cylinder 3. The main air feed pipe 5 is connected to the cylindrical chamber 1 by the conical port 6 which is closed by the automatic safety valve 7 thus precluding any possibility of a back fire into the main air feed pipe 5.

The fuel feed pipe 8 leads into the cone shaped fuel nozzle 9 which is pierced through its apex by the high pressure air duct 10. This high pressure air duct 10 leads from the high pressure air feed pipe 11 through a horizontal hole in the needle valve 4 and thence down through the fuel nozzle 9 into the cylindrical mixing chamber 1. The high pressure air duct 10 is therefore closed by the

needle valve 4 at all times except when the needle valve 4 is raised to its highest position, and when the needle valve 4 is closed and seated in the conical nozzle 2 the conical port 6 and the cone shaped fuel nozzle 9 are also closed by the needle valve 4.

The needle valve 4 is operated and controlled by means of the spring 12, rocker arm 13, and cam 14 driven by the main crank shaft, in a customary manner. The latter three are merely indicated in Fig. 1 for purposes of clearness, as they would vary with the size and type of engine employing this mechanism and except for actuating the needle valve 4 at the proper time and in the proper manner they do not form a part of my improvement. I prefer to use an engine piston having a cup shaped or spherical depression in its top to allow a proper distribution of the fuel spray in the engine cylinder, but except in this particular the engine piston 15, one of the engine valves 16 and the two spark plugs 17—17, (see Fig. 2) are indicated for purposes of clearness and do not form a part of my improvement. The needle valve air relief vents 18, 19 are placed so as to allow a cushioning effect of the air in the upper part of the cylinder chamber 1 at the highest position of the needle valve 4. The water jacket 19 is for cooling purposes.

For a proper functioning of my improvement the engine should draw in through its ordinary intake valves 16 pure air only and compress it on the compression stroke to an initial pressure of from fifty to one hundred or more pounds per square inch before ignition. The air admitted into the cylinder through the intake valve 16 is used for combustion with the subsequently injected fuel. After injection of the fuel by my improvement, ignition through an ordinary electric spark plug and expansion, the engine should release the exhaust gases through its ordinary exhaust valve.

For a proper functioning of my improvement there should be an air compressor connected to the engine to supply air at the required pressure to the main air feed pipe 5, and the high pressure air feed pipe 11, and a means for supplying the fuel to the fuel feed pipe 8 under pressure.

It is to be understood that the mixing chamber 1 is of materially smaller volume than the expansion or combustion chamber 3. The size of the mixing chamber is dependent upon the operating conditions desired, but should be such as to only permit an initial ignition of the fuel therein. It should be of such volume as to contain only sufficient air to cause such initial ignition of the fuel, the ignited fuel being then discharged through the constricted outlet of the mixing or

ignition chamber into the main expansion and combustion chamber 3 wherein the ignited fuel is then completely burned by reason of the air admitted previously through the valve or valves 16.

5 I prefer to employ, so-called, air injection of the fuel into and through the screen of compressed air in the cylinder 1, but when air at the high pressure necessary to supply the high pressure air feed pipe 11 is not available, the fuel feed pipe 8 may be plugged up and the liquid fuel under a high pressure supplied directly through the high pressure air feed pipe 11, thus employing so-called airless or solid injection into and through the screen of compressed air in the cylinder 1.

10 For purposes of illustration, I will take as an example an engine having an initial compression before ignition of sixty pounds per square inch and a final maximum pressure after ignition of 20 two hundred and fifty pounds per square inch. Air at a pressure of two hundred and fifty pounds per square inch is supplied to the main air feed pipe 5, and air at a pressure of three hundred and seventy-five pounds per square inch is supplied to the high pressure air feed pipe 11. The 25 fuel, gasoline, is supplied to the fuel feed pipe 8 under a pressure of two hundred and fifty pounds per square inch.

30 The cam 14 raises the needle valve 4 from its seat in the conical nozzle 2, eight degrees before top dead center of the engine piston's compression stroke. The automatic safety valve 7 at once opens, admitting air under two hundred and fifty pounds pressure per square inch to the chamber 1, and thence through the nozzle 2 to the engine cylinder 3. The area of opening of the automatic safety valve 7 is two or more times larger than the area of the opening in the nozzle 2 so that the pressure in the chamber 1 quickly 35 approaches two hundred and fifty pounds per square inch. The needle valve reaches the top of its lift and opens the high pressure air duct three degrees before top dead center of the engine piston's compression stroke, and the high pressure air at three hundred and seventy-five 40 pounds per square inch drives a metered charge of fuel from the cone shaped fuel nozzle 9, down against and through the compressed air in the chamber 1, and thence with the stream of air 45 already moving through the nozzle 2 into the engine cylinder 3. The fuel in its passage through the chamber 1 and the nozzle 2 becomes finely divided and mixed with the high pressure air and enters the engine cylinder 3 in the form 50 of a finely divided mist or spray.

55 Ignition by means of one or more common electric spark plugs 17-17, placed in the head of the engine cylinder, takes place at top dead center of the engine piston's stroke; the needle valve 4 closes the high pressure air duct seventeen degrees after top dead center of the engine piston's power stroke; the chamber 1 is scavenged by air from the main feed pipe 5 during the downward movement of the needle valve 4, which 60 closes the nozzle 2, twenty-two degrees after top dead center of the engine piston's power stroke. The speed and power of the engine may be governed by a control of the fuel supplied to the fuel feed pipe 8.

65 70 The numerical values of the pressures and of the degrees hereinbefore mentioned are used merely for purposes of illustration and in no way limit or restrict the use to which my improvement may be put.

The pressures of the air in the main air feed pipe 5, and in the high pressure air feed pipe 11 will vary with the type of engine, kind of fuel, and type of air compressor used. When a type of air compression may be employed to supply air to my improvement sufficiently high in pressure and temperature to cause spontaneous combustion of the fuel in the cylindrical chamber 1, then the engine's spark plugs may be removed and a heavy grade of oil used for fuel without the necessity of increasing the compression in the engine cylinder. As stated hereinbefore, a partial ignition of the fuel preferably takes place in the mixing chamber 1, complete combustion taking place in the main cylinder by reason of the air previously admitted therein by valve 16 and compressed. Under such method of operation, the spark plugs 17 may be dispensed with or used merely as a precautionary measure.

20 I am aware that prior to my invention fuel injector valves employing an injection of finely divided fuel mixed with air have been made. I therefore do not claim such a combination broadly; but

25 I claim:

1. In an internal combustion engine, the combination of a working cylinder, a piston operably carried therein, an exhaust port in communication with the upper end of said cylinder, an air inlet port in communication with the upper end of said cylinder, a mixing chamber, a constricted discharge port connecting said mixing chamber with the upper end of said cylinder, said port having an area sufficiently large to discharge a burning fuel mixture without extinguishing the same, a valved hot air port leading into said mixing chamber, a liquid fuel port leading to said mixing chamber, a valve positioned in said mixing chamber, said valve controlling said constricted discharge port, hot air port and liquid fuel port, and means for moving said valve in timed relation to the piston in said working cylinder to periodically uncover first said constricted port, then said hot air port, and then said liquid fuel port to permit the injection of fuel into said mixing zone and cylinder, and finally cover said hot air and liquid fuel ports and close said constricted discharge port.

2. In an internal combustion engine, the combination of a working cylinder, a piston operably carried therein, an exhaust port in communication with the upper end of said cylinder, an air inlet port in communication with the upper end of said cylinder, a mixing chamber, a constricted discharge port connecting said mixing chamber with the upper end of said cylinder, said port having an area sufficiently large to discharge a burning fuel mixture without extinguishing the same, a valved hot air port communicating with said mixing chamber, a liquid fuel port leading to said mixing chamber, and air relief port leading to a point spaced from the end of said mixing chamber opposite said constricted discharge port, a slide valve positioned in said chamber and controlling said ports, and means for moving said valve in timed relation to the piston in said working cylinder so as to first open said discharge port and then uncover said valved hot air port and then uncover the liquid fuel port prior to completion of the compression stroke of said piston.
